UNITED STATES PATENT OFFICE.

RUDOLF ROSNER, OF CHICAGO, ILLINOIS, ASSIGNOR TO CARTER-LONG MAGNETO COMPANY, OF WAUKEGAN, ILLINOIS, A CORPORATION OF ILLINOIS.

IGNITER.

1,332,758.

Specification of Letters Patent.

Patented Mar. 2, 1920.

Application filed April 24, 1918. Serial No. 230,429.

To all whom it may concern:

Be it known that I, RUDOLF ROSNER, a citizen of the United States, residing at Chicago, in the county of Cook and State of Illinois, have invented certain new and useful Improvements in Igniters, of which the following is a specification, reference being had to the accompanying drawings, forming a part thereof.

10 The purpose of this invention is to provide an improved construction of an igniter or spark producer for an internal combustion engine. It consists principally in the improvements in the construction of the 15 parts constituting the interrupter and distributor shown and described as set out in the claims.

In the drawings:

Figure 1 is an axial section of a magneto 20 embodying this invention.

Fig. 2 is a section at the line, 2—2, on Fig. 1.

Fig. 3 is a section at the line, 3—3, on Fig. 1.

25 Fig. 4 is a detail section at line 4—4, on Fig. 2.

Fig. 5 is a section at line, 5—5, on Fig. 3.

Fig. 6 is a top plan view of the distributor.

Fig. 7 is a diagram of the electric circuits.

30 Fig. 8 is a detail similar to Fig. 4, showing a modified construction of one of the posts in the circuit.

In the construction shown in the drawings, 1 is the casing of insulating material, 35 having a diaphragm or head, 2, of like material, below which are mounted in the casing the primary coil, 3, the secondary coil, 4, the core, 5, which is axially hollow to admit the shaft, 6, which is of brass having

40 at its lower end the steel coupling, 7, for connection with means for rotating it. The head, 2, has mounted in it a shaft-bearing member, 8, which affords bearing at 8^a for the shaft, and above said bearing has its cavity enlarged as seen at 8^b, to form an oil cup, 45

said enlarged portion projecting above the insulating head, 2, and adapted to receive exteriorly the sleeve, 10, fitting loosely thereabout for rotation, and exteriorly 50 formed as a cam, 10^a, for operating the interrupter. 11 is a collar driven fast on the shaft and counter-bored taperingly at its

upper end portion which projects above the shaft and split at that portion and interiorly threaded, and provided with an expanding 55 screw, 12. The upper end portion of the sleeve member, 10, has its inner diameter such as to adapt it to be passed onto the upper end of the collar, 11, before the same is expanded, and to be held tightly thereon 60 by expanding of said upper end portion of the collar. Said sleeve has about midway between its ends, that is to say, at the upper end of the cam portion, 10^a, an angle-shaped flange, 10^b, which forms an upwardly-open 65 annular cup or channel encompassing the sleeve. Said upper-end portion of the sleeve is mutilated or cut away at one side as shown at 10^c, rendering it non-circular and thereby adapted to receive and rotate the distributor, 70 13, whose central aperture is similarly shaped to adapt it to pass onto said mutilated collar. From the inner corner of the channel formed by the angle flange, 10^b, oil ducts, 10^d, are bored into the interior of the 75 sleeve, leading thereby into the oil cup formed at 8^b, as above described. The distributor, 13, is provided at its lower side with an annular flange, 13^a, which depends in the annular cup described and operates to 80 close the upper mouths of the oil duct; and the entire construction at this point is adapted, first, to provide convenient access for filling the oil cup, and, second, to prevent the discharge of oil through the in-leading 85 apertures which would otherwise tend to result by centrifugal action from the rotation of the device. The interrupter lever, 15, is mounted upon the head or diaphragm, 2, of the case, by means of a bracket or mounting member, 16, secured to said diaphragm, and having at one end a post, 17, upon which the interrupter lever, 15, is pivoted, and at the other end an abutment, 16^a, between which and the opposite end of the 90 interrupter lever, the spring, 18, reacts for yieldingly holding the lever toward the cam, and the contact terminal, 15^b, of said interrupter lever toward the contact terminal, 19^b, mounted upon the bracket, 19, which 100 is mounted upon the inside of the casing and secured thereto with the binding post, 19^a, to which the circuit wire from one pole of the battery for energizing the primary

coil is secured. The interrupter lever has mounted upon it intermediate its ends an abutment consisting of an insulating roll, 15^a, for encounter of the cam. One end of the primary coil wire is grounded on the frame as diagrammatically indicated at 34 on Fig. 7. The other end of the primary coil wire is connected as indicated at 17^b, to the base of a post, 17^a, with which the interrupter lever mount or bracket, 16, is provided, situated at a short distance from the pivot post, and electrically connected through the condenser, 38, with the bracket, 19. The two posts, 17 and 17^a, are each provided at their upper ends with annular grooves, 17^c and 17^d, and there is provided a bridge piece 20, for connecting the posts above the interrupter, said bridge piece having notches, 20^a and 20^b, for engaging the annular grooves at the upper ends of the posts, 17 and 17^a, respectively, said two notches being preferably in directions transverse to each other so that the bridge piece having been first engaged with one of the posts, as the post, 17, by a longitudinal thrust,—the notch for that engagement being in the end of the bridge piece,—may be engaged with the other post by swinging about the engagement already made with the first post to engage the transversely-extending notch with the groove of said post, 17^a. It will be understood that the fork fingers or prongs formed by the notches mentioned in the bridge piece may be slightly distorted so as to cause the resiliency of the said fork fingers to produce a sufficiently effective frictional engagement with the annular grooves of the post to cause the bridge piece to be securely retained when it has been put in place. For positioning and retaining the spring, 18, which reacts upon the interrupter lever for holding it toward the cam and closing the circuit at the proper position of the cam, there is provided a guide pin, 21, which is mounted loosely both in the interrupter lever and in the abutment, 16^a, against which the spring is stopped at the opposite end. For convenience in assembling without the use of tools and causing the guide pin and spring to be safely retained after they are once assembled, the guide pin has a cross pin, 21^a, which enters a slot in the abutment, 16^a, and on the guide pin, 21, there is placed a washer, 22, against which the spring bears for being stopped by the abutment. The spring being first lodged on the pin, the end of the pin protruding from the spring, is inserted through the aperture provided for its engagement with the interrupter lever, and the inserted end of the pin is thrust back through said aperture until the other end of the pin can enter the seat provided for it in the abutment, and it is then thrust in the opposite direction for

carrying the cross pin, 21^a, into the slot, 16^b. The pin, 21, thus holds the spring positioned properly between the interrupter lever and the abutment to cause its reaction upon the interrupter lever as desired. The washer, 22, is of cushioning and insulating material, and so prevents the spring from forming a part of the circuit, and also diminishes the liability to crystallization of the spring.

It will be recognized that the construction above described in detail permits the assembling and disassembling of the parts constituting the interrupter and its mount, and the distributor without the use of any tools except a screw driver to withdraw the expanding screw from the end of the collar, 11. Instead of merely forming an annular groove in the upper end of the post 17^a, as described, for engagement of the bridge piece, 20, such groove may be produced in effect by boring the post from the lower end to the top and continuing the bore reduced in diameter through the upper end, and inserting down through the central aperture a headed plunger, 17^e, around which within the larger portion of the bore there is lodged a coiled spring, 17^f, stopped at its lower end by a washer, 17^g, which is forced on the lower end of the plunger and retained thereon by expanding the slightly-protruding end portion of the plunger below the washer, forming small fins, 17^h, so that the spring holds the plunger depressed in the post until its head is stopped upon the top of the latter, said head having its under side tapered to form a conical shoulder which cooperates with the upper end of the post to produce substantially a groove at said upper end for engagement of the notched bridge piece, 20, substantially as in the form first described and shown in Fig. 4. This form of post,—that is, having the plunger with the conical-shouldered head equal with the other form, I intend to be indicated by the description "having an annular groove" used in the claims.

One end of the secondary coil wire extends to a contact pin, 25, which is mounted in the diaphragm or head, 2, and is provided with a spring, 25^b, operating with a tendency to thrust the pin upward for contact of its expanded head, 25^a, with the exposed end of a conducting wire, 26, which is embedded in the cover, 27, of the casing, said embedded wire extending to the center of the cover and there being in contact with inner end of the spring, 28, which reacts upon the central contact pin, 29, which is thereby protruded at the center of the cup for contact with the conducting piece, 30, mounted upon the distributor, 13, and extending from a point over the center of the shaft and therefore under the contact pin, 29, outward to one end of the distributor,

and having mounted in it at said end, a 1 spring-protruded contact button, 37, whose expanded head, 37^a, is carried in contact with the inner or under surface of the top 5 of the cover in the rotation of the distributor with the shaft.

Mounted in said cover top are contact posts, 30^x, one for each spark plug 30^a (Fig. 7) which is to be connected with the igniter, that is, one for each cylinder of the engine 10 to be served, said contact posts being exteriorly constructed as binding posts for receiving the wires, and interiorly having their ends flush with the inner surface of the 15 cover, which properly positions them for rubbing contact with the head 37^a, of the contact button, 37, as the distributor revolves.

The cover, 27, is arranged to be secured 20 to the casing by means of two snap catches, 31, 31, and in order to insure the proper positioning of the cover on the casing, these two snap catches are positioned on the casing so as not to be diametrically opposite 25 to each other so that they cannot both be engaged unless the cover is correctly positioned with respect to the case, and the user will thereby be informed when the cover is mispositioned. For engaging the catches, 30 bosses, 32, 32, are formed at proper positions not directly opposite each other at the lower edge of the cover, having notches to receive the engaging ends of the catches, and sloped from both ends to the edge of 35 the notch for deflecting the catch nose preparatory to its snapping into the notch.

The condenser which may be located at any convenient position within the casing is conventionally represented at 38.

40 In Fig. 7 which is a diagram of the several electric circuits, 33 represents the "ground" which is to be understood as the frame of an engine upon which this device is to be mounted, by means of a non-insulated metal bracket, 1^a, said bracket affording means for connecting within the casing the lower terminals of the coils, 3 and 4, said terminals indicated at 34 and 35. At 36 is indicated the grounded side of the 45 energizing battery, 37. The other parts shown in this diagram are denoted by reference numerals as in the other figures.

50 I claim:—

1. In an igniter, in combination with an 55 insulating casing, primary coil and primary circuit comprising a conducting post carried by the casing; an interrupter lever and a fulcrum post therefor supported on the casing, and a bridge-piece from said binding post to said fulcrum post, said fulcrum post and bridge-piece being constructed for disengagably interlocking with each other for retaining the interrupter lever on the fulcrum post.

60 2. In a structure such as set out in claim

1 foregoing, the bridge-piece being engaged with the fulcrum post at a point thereon immediately adjacent to the lever and by said engagement held in contact with the lever.

3. In a construction such as set out in 70 claim 1, said posts having each an annular groove near the upper end, and the bridge-piece having notches for engaging the groove extending in directions transverse to each other.

75 4. In an igniter in combination with an insulating casing, primary coil and circuit, an interrupter lever fulcrumed at one end and moving at the opposite end for opening and closing the circuit and having intermediate its ends an insulating abutment; an interrupter cam on the interrupter shaft encountering said abutment, and a spring which holds the interrupter lever against the cam reacting on said lever at the end 85 remote from the fulcrum; whereby a spring of minimum resistance may be employed.

5. In a structure such as set out in claim 4 foregoing, a support for the interrupter lever fulcrum, a fixed conducting post in the 90 circuit and a conducting bridge from such post to the lever fulcrum, said support having an abutment stopping the spring opposite the lever, and a seat for the spring on the abutment formed of insulating material, whereby the circuit is completed without including the spring therein.

6. In an igniter, in combination with a casing, the primary and secondary coils and a hollow core therein, a shaft extending axially through the core, the casing comprising an insulating head or diaphragm, above the coils and core; a shaft-bearing member in the insulating head, having an enlarged cavity above the bearing of the 105 shaft therein forming an oil cup around the shaft; a collar fast on the end of the shaft within the oil cup and extending thereabove; a sleeve comprising at the lower end an interrupter-operating cam, and means 110 for making it fast on said upper end of the collar, said sleeve having its cavity enlarged below its seat on the collar for revolving it about the oil cup.

7. In a structure such as set out in 115 claim 6 foregoing, the means for making the sleeve fast on the collar, consisting in that the collar is taperingly counterbored and split and interiorly threaded at its part which extends above the shaft, and an expanding screw screwed into said counterbore.

8. In a structure such as set out in claim 6 foregoing, the upper end of the sleeve being non-circular; and a distributor having 120 an aperture for engaging said non-circular upper end removably mounted thereon.

9. In a structure such as set out in claim 6, the sleeve having an exterior angle-shaped flange forming an annular pocket at a plane 125 130

overhanging the oil cup, and an oil duct leading from said pocket for discharge into the oil cup.

10. In a structure such as set out in claim 5 foregoing, a distributor mounted upon the sleeve for rotation therewith, said sleeve having an exterior angle-shaped flange forming an annular pocket above the oil cup, said distributor having at its lower end an an-

nular flange which enters said pocket, and is adapted to cover the same for preventing oil being thrown therefrom in the rotation of the shaft.

In testimony whereof, I have hereunto set my hand at Chicago, Illinois, this 16th day 15 of April, 1918.

RUDOLF ROSNER.
